UNITED STATES PATENT OFFICE

BENJAMIN F. FAUNCE, OF WESTMONT, JOHNSTOWN, AND WALTER H. STATLER, OF JOHNSTOWN, PENNSYLVANIA, ASSIGNEES TO BETHLEHEM STEEL COMPANY, A CORPORATION OF PENNSYLVANIA

MINE CAR

Application filed September 7, 1929. Serial No. 391,084.

Our invention relates to the construction of metal railway cars and more especially to that type of cars known as mine cars which are adapted for use in mines for hauling coal and ore, or the like material.

One of the objects of our invention is to produce a car of less height than that of cars ordinarily employed in which the bottom or floor of the car is low relative to the track, in order to give greater stability of the car on the track, by carrying the load close to the rails, and at the same time for a given head room the car will have greater carrying capacity and will be especially adapted for use in low or thin seam mines.

A further object of the invention relates to the manner of constructing a portion of the car floor to form the running gear housings by means of transversely extending trough shaped plate cross-sills adapted to be secured to and reinforce the plate sides of the car, and in which are formed integrally therewith extensions over the wheels constituting hood or shield coverings therefor.

Another object of our invention is to construct a mine car in which the floor is rigidly constructed entirely of metal and braced in such a manner that the bottom floor of the car will not buckle or break as is the case when a flat plate car floor bottom is used. To this end the car is formed with a central longitudinal ridge and a plurality of intermediate transverse ridges dividing the bottom of the car into bin like recesses between the ridges and the sides of the car.

A further object of our invention is to construct a mine car without doors in which the bottom floor and sides are rigidly attached together, which is adapted for use with tipples either for the forward discharge of the load or in a rotary type tipple as desired.

Other objects of our invention relate to certain novel features of construction, combination and arrangement of parts which will be hereinafter more fully described and particularly pointed out in the appended claims, reference being had to the accompanying three sheets of drawings in which:

Fig. 1 is a top plan view of a mine car embodying our improvements;

Fig. 2 is a side elevation of the same car;

Fig. 3 is a vertical longitudinal section taken through the wheel housings on the line 3—3 of Fig. 1;

Fig. 4 is a vertical longitudinal section taken near the longitudinal center sill of the car on the line 4—4 of Fig. 1;

Fig. 5 is an end elevation;

Fig. 6 is a vertical transverse section taken on the line 6—6 of Fig. 1;

Fig. 7 is a vertical transverse section taken on the line 7—7 of Fig. 1;

Fig. 8 is a top plan view of one of the transverse reinforcing trough shaped plate cross-sill members, detached which is adapted to form a housing for the running gear;

Fig. 9 is an enlarged longitudinal section taken on the line 9—9 of Fig. 1 on the center line of the car at the end thereof; and

Fig. 10 is a detail view illustrating a modified form of construction, in which the lower edge of the side sheet is flanged and attached directly to the floor plates.

Referring now to the characters of reference on the drawings the numeral 1 indicates the end and 2 the central floor plates which are connected together at an intermediate point transversely of the car by means of a pair of trough shaped plate cross-sills 3 each having a flat top floor portion 4 in which is integrally formed upwardly extending wheel housings 5, and downwardly inclined leg portions 6 having flanged edges as at 7, by means of which they are riveted to the end and center floor plates 1 and 2 respectively thereby forming a floor with truncated parallel corrugations. The center floor plate 2 is further reinforced at its central portion by means of angles 2'.

The sides 8 of the car are formed of a single sheet of metal having their upper edge portion bent or rolled over to form a tubular top edge 9 with the edges 10 bent flat against the outside of the side sheet and riveted thereto. The central portion being further reinforced by means of an angle 11. The lower edges of the side plates 8 are secured to the floor plates 1 and 2 and the trough shaped

cross-sills 3 in any approved manner, as by means of a separate angular member 12 as indicated in Fig. 1, 2, 3, 4, 6 and 7 or the lower portion of the side sheets may be formed with an integral flange 13 as shown in Fig. 10, and riveted directly to the floor plates and trough shaped cross-sills 3.

To further stiffen the sides of the car, gusset braces 14 having flanged edges 15 are attached to the car sides and the top of the trough shaped cross-sills 3.

The car ends 16 are each formed of a single sheet of metal having their upper portion rolled to form a tubular top 16', the edge portion being bent flat as at 17 and riveted to the body of the sheet in a similar manner to that of the side sheets. The end sheets 16 are connected to the side sheets 8 and the end floor plates 1, by means of corner angles 18 and 19 respectively.

Openings 20 are formed in the end sheets through which extend buffer blocks 21 preferably formed of wood of one or more pieces. The inner end of each buffer block is adapted to rest on the top of the end sheet 1 on the inside of the car and is attached thereto by means of bolts, while the opposite end extends beyond the end of the car and has a buffer plate 22 of U-section mounted thereon to receive the buffing shocks and strains.

The rear ends of the buffer blocks 21 each engages a transverse bent plate 23, the lower flanged edge 24 of which is attached to the floor plates 1, while the sides of the rear ends of the buffer blocks 21 are received between the Z-bars 25 having their lower flanges 26 riveted to the floor plates 1 while the upper flanges 27 are attached to cover plates 28 by means of bolts.

The cover plates 28 are flanged at their forward ends as at 29 and riveted to the end plates 16, while the inner longitudinal sides are flanged as at 30, and are riveted to the upwardly extending vertical flanged legs 31 of a channel center sill 32. This channel center sill 32 extends the entire length of the car having its web longitudinally disposed thereof with its ends supported by the buffer blocks 21, while the intermediate portions are supported by the top flat side faces 4 of the trough shaped cross-sills 3.

Vertical stiffening plates 33 flanged at their sides and lower edges as at 34 are riveted to the central floor plate 2 and the inner inclined sides 6 of the trough shaped cross-sills 3, the top edge of the vertical stiffening plate being attached directly to the legs 31 of the center sill 32. Other vertical stiffening plates 35 and 36 flanged at their lower and side edges as at 37 are riveted to the end floor sheets 1 and to the outer inclined sides 6 of the trough shaped cross-sills 3, with the forward flanged edges engaging the bent plate 23 and their top edges riveted to the legs 31 of the center sill 32 in a similar manner to that of the stiffen-

ing plates 33. The bent plates 23 are also connected to the web of the center sill 32 by means of angles 38. 39 indicates the draw-bar ends each having their rear ends secured to the ends of the center sill 32, buffer blocks 21 and end floor plates 1 by means of bolts 40. These bolts also pass through a reinforcing bar 41. The outer end of each draw-bar end is bent upwardly and outwardly and spaced apart by means of a filler block 42 and is secured in position by means of a bolt 43. A perforation is formed in the outer portion of each of the draw-bar ends 39, which registers with the perforations formed in the bumper plate 22 reinforcing bar 41 and buffer block 21 for receiving the usual coupling pin 44.

Journal boxes 45 are attached to the underside of the flat floor portions 4 of the trough shaped cross-sills 3 near the ends thereof by means of rivets which are further reinforced by means of filler plates 46. Axles 47 are journaled in the boxes 45 having wheels mounted thereon as at 48 adapted to extend into the hoods 5 formed in the trough shaped plate cross-sills 3. It will be noted that the trough shaped plate cross-sills 3 not only form a portion of the car floor, but a housing for the axle and journal boxes and a hood or shield for the wheels thereby allowing the main body of the car floor to be below the bottom of the axles and near the rails thereby giving greater carrying capacity to the car at the same time we are able to form a very strong car body in such a manner as to eliminate the necessity of using side sills.

Although we have described and illustrated our invention in considerable detail, we do not wish to be limited to the exact and specific details thereof, as shown and described, but may use such modifications in, substitutions for or equivalents thereof, as are embraced within the scope of our invention or as pointed out in the claims.

Having thus described our invention what we claim and desire to secure by Letters Patent is:

1. In a car structure, comprising a body having sides and end walls, a floor extending the full length of the car secured to the sides and end walls having transversely spaced housings formed therein, and a longitudinal ridge connecting the spaced housings and end walls together.

2. In a car structure, a body having walls and a floor extending the full length of the car, spaced housings extending transversely of the floor and forming a portion thereof, running gear for the car mounted in the spaced housings, and a longitudinal ridge connecting the central portions of the spaced housings and end walls together.

3. In a car structure, a body having walls and a floor, spaced housings of trough section extending transversely thereof the entire

width of the car and forming a portion of the car floor, running gear for the car mounted in the spaced housings having journal bearings rigidly secured thereto, and hoods for the wheels of the running gear formed integral with the spaced housings.

4. In a car structure, a body having walls and a floor, spaced trough shaped housings of substantially uniform cross-section throughout the major portion of their lengths extending transversely thereof and forming a pair of transverse ridges for a portion of the car floor, running gear for the car mounted entirely within the spaced housings, hoods for the wheels of the running gear formed integral with the housings, and a longitudinal center-sill extending over and connecting the central portions of the spaced housings together and forming a central ridge for the car floor.

5. In a car structure, a body having walls and a floor, spaced inverted trough shaped cross-sills of substantially uniform cross-section throughout the major portion of their lengths extending transversely thereof and forming a portion of the car floor, running gear for the car mounted entirely in the spaced inverted trough shaped cross-sills, hoods for the wheels of the running gear formed integral with the inverted trough shaped cross-sills, and flat plates secured to the edges of the spaced inverted trough shaped cross-sills and the walls of the car body.

35 6. In a car structure, comprising a body having side and end walls, running gear therefor, a floor having a longitudinal central ridge, trough shaped plate cross-sills of substantially uniform cross-section throughout the major portion of their lengths formed therein and secured to the plate sides of the car at intermediate points, and upwardly extending hoods for the wheels of the running gear struck up from the cross-sills and formed integral therewith.

7. In a car structure, a body having side and end walls, a floor comprising a plurality of spaced trough shaped cross-sills and flat floor plates secured together, a channel center-sill forming the central longitudinal portion of the car floor extending over the central portions of the cross-sills and secured thereto, and means for securing the floor to the side and end walls.

55 8. In a car structure, a body having side and end walls, a floor comprising a plurality of spaced trough shaped cross-sills with flanged edges, said spaced trough shaped cross-sills being of substantially uniform cross-section throughout the major portion of their lengths and extending transversely of the car below the center sill and attached to the car sides, and flat plates secured to the flanged edges of the spaced trough shaped

sills and secured to the sides and ends of the car.

9. In a car structure, a body having side and end walls, a floor comprising a longitudinal center-sill forming a central ridge for the car, a plurality of spaced transverse trough shaped cross-sills mounted below the center-sill forming ridges for a portion of the floor, a flat floor plate disposed centrally for connecting the spaced trough shaped cross-sills together, flat end floor plates for connecting the transverse trough shaped cross-sills to the car ends, and means for connecting the ends of the transverse trough shaped cross-sills and flat floor plates to the car sides.

10. In a car structure, a body having side and end walls, a channel center sill having a horizontally disposed web and upwardly extending flanges, and a car floor having blind recesses formed therein on either side of the center sill.

11. In a car structure, a body having side and end walls, a channel center sill extending the full length of the car having a horizontally disposed web and upwardly extending flanges, a car floor with truncated parallel corrugations on each side of the center sill, and stiffening members for connecting the corrugated floor and center sill together.

12. In a car structure, a body having side and end walls of sheet metal having their upper edges bent over and rolled into a tubular shape with their ends bent flat and riveted to the outside face of the sheets, a reinforcing angle attached to the bent flat portion of the side sheets intermediate its ends, a channel center sill having a horizontally disposed web and upwardly extending flanges, a car floor formed with truncated parallel corrugations on each side of the center sill, and stiffening members for connecting the corrugated floor and center sill together.

13. In a car structure, a body having side and end walls, a floor comprising a plurality of spaced inverted trough shaped cross-sills extending transversely of the car, flat floor plates between the cross-sills and the end walls and connected thereto, bumper blocks seated upon the end floor plates and secured thereto, a channel center sill having its web horizontally disposed with upwardly extending flanges supported by the bumper blocks and cross-sills, and stiffening members for connecting the floor plates and the center sill together.

14. In a car structure, a body having side and end walls, a floor comprising a plurality of spaced inverted trough shaped cross-sills extending transversely of the car forming housings for the car running gear, upwardly extending hoods for the car wheels formed integral with the cross-sills, flat floor plates between the cross-sills and the end walls and

connected thereto, bumper blocks seated upon the end floor plates and secured thereto, a channel center sill having its web horizontally disposed with upwardly extending flanges supported by the bumper blocks and cross-sills, and stiffening members for connecting the floor plates and the center sill together.

15. In a car structure, a body having side and end walls, a floor comprising a plurality of spaced inverted trough shaped cross-sills extending transversely of the car, flat floor plates between the cross-sills and end walls and connected thereto, bumper blocks secured to the top of the flat end floor plates and extending outwardly beyond the end of the car, a transverse bent plate secured to each end floor plate, and spaced Z-bars at each side of the bumper blocks secured to the end floor plates between the bent plate and the end walls of the car.

16. In a car structure, a body having sides and end walls, a floor comprising a plurality of transversely arranged spaced inverted trough shaped cross-sills, flat floor plates between the cross-sills and end walls and connected thereto, a transverse bent plate secured at an intermediate point to the top of each end floor plate, bumper blocks secured to the top of the flat end floor plates and extending outwardly beyond the ends of the car, Z-bars at each side of the bumper blocks secured to the top of the end floor plates between the bent plates and the end walls of the car, a channel center sill engaging the top of the cross-sills and bumper blocks, and means for securing the center sill to the top of the bumper blocks and floor plates.

17. In a car structure, a body having sides and end walls, a floor comprising a plurality of spaced inverted trough shaped cross-sills forming housings for the running gear mounted therein, hoods for the wheels of the running gear formed integral with the cross-sills, flat floor plates between the cross-sills and end walls and connected thereto, a transverse bent plate secured centrally to the top of each end floor plate, bumper blocks secured to the top of the flat end floor plates and adapted to extend through a hole in the end wall outwardly beyond the ends of the car, Z-bars at each side of the bumper blocks and secured to the top of the end floor plates between the bent plates and the end walls of the car, a channel center sill engaging the top of the cross-sills and bumper blocks, and means for securing the center sill to the top of the bumper blocks and floor plates.

18. In a car structure a body having side and end walls, a floor comprising a plurality of spaced inverted trough shaped cross-sills of substantially uniform cross section throughout the major portion of their lengths forming housings for the running gear extending transversely of the car, flat floor

plates between the cross-sills and the car end walls below the center of the axles of the running gear, means for connecting the cross-sills and plates together, means for connecting the side and end walls to the floor, and reinforcing gusset braces between the side walls and tops of the cross-sills.

19. In a car structure, a body having side and end walls, a floor comprising a plurality of spaced inverted trough shaped cross-sills of uniform cross section throughout the major portion of their lengths extending transversely of the car below the center sill and forming housings for enclosing the running gear, hoods for the wheels of the running gear formed integral with the cross-sills, flat floor plates between the cross-sills and the car end walls, a flange formed on the lower edge of the side sheets riveted to the side edges of the floor, and gusset braces between the side walls and the tops of the cross-sills.

20. In a car structure, a body having sides and end walls, a floor comprising a plurality of spaced inverted trough shaped cross-sills forming housings for the running gear mounted therein, hoods for the wheels of the running gear formed integral with the cross-sills, flat floor plates between the cross-sills and end walls and connected thereto, a flange formed on the lower edge of the side sheets riveted to the side edges of the floor, gusset braces between the side walls and the tops of the cross-sills, a transverse bent plate secured centrally to the top of each end floor plate, bumper blocks secured to the top of the flat end floor plates and adapted to extend through a hole in the end wall outwardly beyond the ends of the car, Z-bars at each side of the bumper blocks secured to the top of the end floor plates between the bent plates and the end walls of the car, a channel center sill engaging the top of the cross-sills and bumper blocks, and means for securing the center sill to the top of the bumper blocks and floor plates.

21. In a car structure, a body having side and end walls, a floor comprising a plurality of spaced transverse trough shaped cross-sills, flat floor plates between the cross-sills and the end walls, means for connecting the floor to the side and end walls, bumper blocks seated on the top of the end floor plates each adapted to extend through an opening in the end walls, a channel center sill supported by the cross-sill and bumper blocks and secured thereto, a transverse bent plate secured centrally to the top of each end floor plate for engaging the rear end of each bumper block, Z-bars at each side of the bumper block secured to the top of the end floor plates between the bent plates and the end walls of the car, a reinforcing bar mounted on the bumper blocks cover plates on top the bumper blocks on each side of the center sill, means for securing the cover plates to the center-sills and

end walls, a connection between the bent plate and the center sill, a draw bar end attached to each end of the center sill, a filler block between the draw bar end and the reinforcing bar and a bumper plate attached to the outer end of each bumper block.

22. In a car structure, a body having side and end walls, a floor having a central longitudinal ridge and a plurality of transverse ridges, said floor comprising a plurality of spaced trough shaped cross-sills of uniform cross-section throughout the major portion of their lengths extending transversely of the car and having their ends attached to the car sides to form the transverse ridges for the floor, wheel hoods formed integral with the spaced trough shaped cross sills, a center-sill extending over the cross-sills and secured thereto and forming the central longitudinal ridge for the floor, and flat plates secured to the spaced trough shaped sills and secured to the sides and ends of the car.

In testimony whereof I hereunto affix my signature.

WALTER H. STATLER.

In testimony whereof I hereunto affix my signature.
